(21) Appl. No.: **29/936,737**

Primary Examiner — Michelle E. Wilson

(22) Filed: **Apr. 10, 2024**

Assistant Examiner — Clese Moore, Jr.

(30) **Foreign Application Priority Data**

(74) Attorney, Agent, or Firm — Dickinson Wright PLLC

Oct. 11, 2023 (EM) 015036816

(57) **CLAIM**

(51) **LOC (15) Cl.** **12-15**

The ornamental design for a tire sidewall, as shown and described.

(52) **U.S. Cl.**

DESCRIPTION

USPC **D12/605**

FIG. 1 is a perspective view of a tire sidewall showing my design;

(58) **Field of Classification Search**

FIG. 2 is a front elevation view of the tire sidewall of FIG. 1;

USPC D12/604, 605

FIG. 3 is a rear elevation view of the tire sidewall of FIG. 1;

CPC B60C 13/00; B60C 1/00

FIG. 4 is a side elevation view of the tire sidewall of FIG. 1;

See application file for complete search history.

FIG. 5 is a side elevation view taken from the opposite side of that shown in FIG. 4; and,

(56) **References Cited**

FIG. 6 is a detailed view taken from FIG. 1.

U.S. PATENT DOCUMENTS

The broken line disclosure in the drawings depicts environmental subject matter forming no part of the claimed design.
